[57] CLAIM

The ornamental design for a roadster, as shown and
described.

DESCRIPTION

FIG. 1 is a side elevational view of a roadster showing
my new design.

FIG. 2 is an enlarged fragmentary perspective view of
the passenger compartment having a rear jump seat
area.

FIG. 3 is a rear perspective view with the convertible
top in raised condition.

FIG. 4 is a front perspective view with the convertible
top down.

FIG. 5 is a rear perspective view with the convertible
top in raised condition but from the opposite side of
FIG. 3.

FIG. 6 is a front perspective view with the convertible
top down but from the opposite side of FIG. 4.

FIG. 7 is an enlarged fragmentary perspective view of
the passenger compartment without a rear jump seat
area.
